(**) Term: **14 Years**

(57) **CLAIM**

(21) Appl. No.: **29/286,610**

We claim the ornamental design for a combined lighting device and charger, as shown and described.

(22) Filed: **May 14, 2007**

DESCRIPTION

(51) LOC (8) Cl. **13-02**

FIG. 1 is a right top perspective view of the combined lighting device and charger of the present invention.

(52) U.S. Cl. **D13/108; D26/51**

FIG. 2 is a front view of the combined lighting device and charger of the present invention.

(58) Field of Classification Search D13/107-110,

FIG. 3 is a back side view of the combined lighting device and charger of the present invention.

D13/118-119, 184; D14/251, 253, 432, D14/434; D26/51, 72; 320/107-115

FIG. 4 is a left side view of the combined lighting device and charger of the present invention.

See application file for complete search history.

FIG. 5 is a right side view of the combined lighting device and charger of the present invention.

(56) **References Cited**

FIG. 6 is a top view of the combined lighting device and charger of the present invention; and,
